MEANS FOR HOLDING CHASERS

Ernest T. Eyshe and Robert R. Finn, Springfield, Vt., assignors to Jones & Lamson Machine Company, Springfield, Vt., a corporation of Vermont

Original application February 25, 1930, Serial No. 431,498. Divided and this application August 25, 1932. Serial No. 630,352

6 Claims. (Cl. 10—104)

This invention relates to means for holding chasers, more particularly of the tangent type in a manner suitable for employment in screw cutting dies and has for an object to provide 5 means which will facilitate the return of the chasers after removal from their holding means into exactly the same positions in which they were positioned before removal, or into positions removed from their former positions by definite 10 determined amounts, and by which if desired micrometer adjustment is possible.

This application is a division of our application Serial No. 431,498, filed February 25, 1930, for Automatic dies.

15 For a more complete understanding of this invention, reference may be had to the accompanying drawing in which

Figure 1 is a fragmentary side elevation of a die embodying this invention.

20 Figure 2 is a front elevation of the same, one of the chaser holders being shown partly in section.

Figure 3 is a view similar to a portion of Figure 2, but to a larger scale.

25 Figure 4 is a view similar to Figure 3, but showing the chaser released.

Figures 5 and 6 are views similar to Figures 3 and 4, respectively, but showing a modified construction including a micrometer adjustment.

30 Figure 7 is a fragmentary top plan to a smaller scale of the construction of Figures 5 and 6.

As shown in Figures 1 and 2, the chasers 10 may be carried by a die body 1 through the medium of chaser holders 6, each having a dovetail portion 7 slidably fitting a correspondingly shaped groove 5 in the die body, sliding of these holders from and toward the axis of the body serving to open or close the die as more fully disclosed in the parent application for patent 35 hereinbefore mentioned. These cooperating parts, including the forward face of the body 1 and the mating rear face of the holders 6, should be ground and lapped accurately to form so that the die holders may be held accurately 40 in proper position. There may be clearance at the root of the portion 7. The rear face 8 of each die holder rests squarely and flat against the forward face portion 4 of the body member 1. Thus the chaser holder is accurately supported 45 free from liability of rocking or other play. One side face of each holder 6 is provided with means for receiving and accurately holding a chaser 10, which, as shown, is of the tangent type.

50 In order to secure the chasers with capability of accurate adjustment but at the same time

firmly in any desired adjusted position, the side face 11 of each holder is shown as provided with a dovetail slot 12 and the chaser 10 is provided with a mating dovetail portion 13. Means are provided for fixing the chasers longitudinally 60 relative to their holders. The rear face 15 of each chaser at the dovetail 13 is provided with ratchet serrations and fitting these serrations and 65 slide in an aperture 18 in a corresponding holder, in the construction shown in Figures 2, 3 and 4, is a plug 19 having its outer end face 20 shaped to mate the serrations 15. As shown this plug 19 is pressed into contact with the chaser as by means of a spring 21 seated in a socket in the rear end of the plug and reacting 70 against the rear face 22 of a chamber 24 within which the plug 19 is slidably fitted. The plug 19 is laterally perforated as at 191 for the passage therethrough of a stem 192 of a locking and 75 releasing plug 193. The stem 192 is smaller than the perforation 191 but has a head 194 at its inner end having its opposite end faces beveled which is of a size to slidably fit this perforation. This head is also slidable into and out of a socket portion 195 in the chaser holder. The plug 193 80 has a threaded portion 196 engaging in a mating threaded opening 197 in the chaser holder and has a head 198 which at its end may be provided with a polygonal socket 199 to receive an actuating tool by which it may be turned. 85 At the inner end of the threaded portion is a circular shoulder 200 which may enter a counterbored portion 201 at the outer end of the plug passage. This shoulder is of sufficiently smaller 90 diameter than the counterbore to permit the plug 19 to adjust itself to the toothed face of the chaser, but the difference in size is too small to permit the lug to become disengaged therefrom. By unscrewing the plug 193, however, this shoulder 95 is first withdrawn from the counterbore and the tapering rear end of the head 194 then engages the upper wall portion of the perforation 191 and wedges the plug 19 against the action of the spring 21 out of engagement with the chaser whereupon the chaser can be removed. 100 The tapering front end of the head 194 exerts a similar releasing action on insertion of the plug 193 after it has been removed for any reason.

The serrations 15 of the chaser may act as a 105 gage in the sharpening operation, at each grinding operation the amount of stock removed being equal to the space between adjacent serrations. The chasers can then be returned to position in the die with assurance that the cutting edges will be in the same relation to the work as before 110

the sharpening, the chaser being moved inwardly the definite increment of one tooth further than its position before sharpening.

In Figures 5, 6 and 7 a modification is shown 5 in which a micrometer adjustment of the chaser can be effected. As there shown the plug 190 is provided with a slot 25 at one side within which normally extends the inner end of a latch plug 26 which is removably held seated in a perforation 27 through a wall of the holder 6 as by means of a split spring ring 270 positioned in a portion 28 of reduced diameter in the plug 26 and engaging the wall of the perforation 27. This plug 190 is slidably mounted in a carrier 30 10 axially rotatable in the holder 6, the plug 19 being eccentrically mounted relative to the axis of this carrier which can be turned as by means of a suitable implement inserted in a polygonal socket 31 in its outer end. By such rotation the plug 19 is moved with a component of motion lengthwise of the chaser thus to move the chaser lengthwise. The plug carrier 30 may be provided 15 with a spring latch to retain it yieldably in any one of a plurality of adjusted angular positions, 20 which, as shown, comprises a plug 35 having a pointed end 36 pressed toward the periphery of the member 30 by a spring 37 housed in a member 370 threaded in the chaser holder so as to enter in any selected one of a series of peripheral 25 recesses 38 therein brought opposite to this pointed end.

It will be noted that each of the various described means which secures the chaser in position is not called upon to take any of the tilting 30 thrusts of the work against the chaser, this all being taken care of by the bearing of the chaser against the solid portion of the holder in contact therewith. Not only does this make for simpler and more rigid and accurate and stronger construction, but it also avoids warping or other distortion of the chasers and holders occasioned by pressure of clamping elements thereon.

From the foregoing description of certain embodiments of this invention which have been 45 presented by way of example, and not of limitation, it should be evident to those skilled in the art that the invention might be embodied in various other forms without departure from its spirit or scope as defined by the appended claims.

50 We claim:

1. In combination, a chaser holder, a chaser of the tangent type carried by said holder with capability of adjustment longitudinally theron, means for retaining said chaser in adjusted position, and means carried by said holder and cooperating with said retaining means actuatable to lock said retaining means in retaining position or to move and hold said means out of retaining position.

60 2. In combination, a chaser holder, a chaser of the tangent type carried by said holder with capability of movement longitudinally thereon, a plug spring pressed against said chaser to hold said chaser in fixed position, and a member movable laterally of the pressing movement of said plug and cooperating with said plug in one position to hold said plug in chaser-holding position and in another position to hold said plug out of chaser-holding position.

76

3. In combination, a chaser holder, a chaser carried by said holder with capability of longitudinal movement thereon, said holder having a socket, a plug in said socket, a spring in said socket for pressing said plug against said chaser, 80 said chaser and plug having engaging faces preventing movement of said chaser when engaged by said plug, said plug having an opening therethrough transverse to its pressing movement, and a member projectable through said opening and having a portion engageable with said plug for removing said plug from contact with said chaser by movement of said member.

4. In combination, a chaser holder, a chaser carried by said holder with capability of longitudinal movement thereon, said holder having a socket, a plug in said socket and slideable therein toward and from said chaser, a spring in said socket for pressing said plug against said chaser, 85 said chaser and plug having engaging faces preventing movement of said chaser when engaged by said plug, said plug having a lateral opening therethrough, and a member projectable through said opening and having a portion engageable with said plug for removing said plug from contact with said chaser by movement of said member.

90 5. In combination, a chaser holder having a

slideway, a chaser having a portion riding in 105 said slideway, said holder having a socket opening into said slideway, a plug slidably fitting in said socket for movement toward and from said chaser, a spring for pressing said plug against said chaser portion, the confronting faces of 110 said chaser portion and plug being serrated whereby said plug when in engagement with said chaser portion holds said chaser against movement relative to said holder, said holder having a passage intersecting said socket, said plug having an opening therethrough laterally of its direction of sliding movement, and a member axially movable in said passage and projectable through said opening, said member having a large diameter portion when in said opening holding said plug 115 retracted from said chaser.

120 6. In combination, a chaser holder having a

slideway, a chaser having a portion riding in 125 said slideway, said holder having a socket opening into said slideway, a plug in said socket, a spring for pressing said plug against said chaser portion, the confronting faces of said chaser portion and plug being serrated whereby said plug when in engagement with said chaser portion holds said chaser against movement relative to 130 said holder, said holder having a passage intersecting said socket, said plug having an opening therethrough laterally of its sliding direction, and a member axially movable in said passage 135 and projectable through said opening, said member having a larger diameter portion when in said opening holding said plug retracted from said chaser and a portion engageable with said plug when said large diameter portion is out of engagement therewith for holding said plug in chaser-engaging position.
